UNITED STATES PATENT OFFICE.

JOHN J. PIKE, OF CHELSEA, MASSACHUSETTS.

CARRIAGE-JACK.

Specification of Letters Patent No. 30,346, dated October 9, 1860.

To all whom it may concern:

Be it known that I, JOHN J. PIKE, of Chelsea, in the county of Suffolk and State of Massachusetts, have invented a new and useful or Improved Carriage-Jack, and do hereby declare the same to be fully described in the following specification and illustrated in the accompanying drawings, of which—

Figure 1, is a top view, Fig. 2, a side elevation, Fig. 3, a longitudinal and vertical section and Fig. 4, a transverse and vertical section of it, the latter figure being so taken as to exhibit the arrangement of the lever catches by which the lifting lever of the jack is maintained either at its highest or at its lowest position.

In the drawings A, denotes a frame composed of a bed plate *a*, and two pairs of standards or posts *b*, *b'*, *c*, *c'*, they being arranged as represented. The two front posts *b*, *b'* support the fulcrum pin *d*, of a lifting lever *B*, which is placed between them and the parts *c*, *c'*.

The lower end of a notched bearing bar or lever *C*, rests on the inferior or lower arm of the lever *B*, while the said bar *C*, is arranged at an acute angle with the lever *B*, and extends between the two posts of each pair *b*, *b'* or *c*, *c'* and is supported by a fulcrum or pin *e*, passed through the two posts *c*, *c'* and such bar *C*.

The bar *C*, is constructed with a series of seats or right angular notches *f*, *f*, *f*, arranged along its upper surface as shown in the drawings. Furthermore a screw *g*, is not only passed upward through the slot *h*, of a cap plate *i*, (which is fastened to the upper surface of the smaller arm of the lever *B*, and formed as shown more particularly in Fig. 5, which is a top view of the lever *B*,) but is screwed into the lever *C*, and with the plate *i*, serves to connect the two levers in such manner as to cause the front end of the lever *C*, to move either upward or downward with that of the lever *B*, while the latter is being turned on its fulcrum.

Two lever stops *k*, *l*, formed as shown in Fig. 4, are applied to the inner side of one of the posts *c*, *c'*, by means of two fulcrums *m*, *n*, projecting from the post. The opposite ends of the longer stop *l*, are bifurcated,

the outermost prong of the upper fork being longer than its inner prong, the lower arm of the upper lever stop *k*, extends into the fork of the upper arm of the stop *l*, while the fork of the lower arm receives a spring *o*, affixed to the post *c*. When the lever *B*, is depressed so as to rest on a pin *p*, extending through the posts *c*, *c'* the said spring *o*, will cause the longer stop to extend over the lever so as to estop it from being elevated, so when the lever *B*, is raised to its highest position (that is up against the lever *C*.) the upper stop by the action of the spring, and the lower stop, will be forced to project underneath the lever in such manner as to retain it in its highest position. By pressing inward the upper arm of the lower lever stop both lever stops may be moved simultaneously on their fulcra and so as to carry either the upper arm of the upper stop, or the lower arm of the lower stop away from the lever *B*, as circumstances may require in order to enable such lever to be either raised or lowered on its fulcrum.

By means of the notched bar or lever *C*, constructed arranged and applied to the frame *A*, and the lever *B*, in manner as specified the carriage jack can be readily adjusted to the axle of any vehicle preparatory to the raising of such axle with the jack. To accomplish the adaptation of the jack to an axle, the former is to be pressed forward under the latter until the axle may enter one of the notches of the bar *C*. This having been done, the rear end of the lever *B*, is to be depressed. This will elevate the lever *C*, and the axle resting on it.

The advantage of my improved jack over that having one lever only (which of necessity must have means of adjusting its fulcrum in order that the lever may be properly applied to a carriage) is to be found not only in the case by which it may be adapted to an axle, but in the increased leverage which is applied by it in order to effect the elevation of the axle. I therefore do not claim a carriage jack as constructed with but one lever, furnished with an adjustable fulcrum, but

I claim—

1. My improved carriage jack as con-

structed with the extra bearing lever C, combined and arranged with the lifting lever B, and the supporting frame A, substantially in manner and so as to operate as hereinbefore described.

2. The combination and arrangement of the two spring stopping levers *k*, *l*, and the

pin *p*, with the levers B, and C, applied within the frame A, and with respect to one another as specified.

JOHN J. PIKE.
